No. 739,629.

PATENTED SEPT. 22, 1903.

M. M. WOOD.

INDICATOR FOR LIQUID CONTAINING VESSELS.

APPLICATION FILED DEC. 12, 1902.

NO MODEL.

UNITED STATES PATENT OFFICE.

MONTRAVILLE M. WOOD, OF SCHENECTADY, NEW YORK, ASSIGNOR TO
GENERAL ELECTRIC COMPANY, A CORPORATION OF NEW YORK.

INDICATOR FOR LIQUID-CONTAINING VESSELS.

SPECIFICATION forming part of Letters Patent No. 739,629, dated September 22, 1903.

Application filed December 12, 1902. Serial No. 134,982. (No model.)

To all whom it may concern:

Be it known that I, MONTRAVILLE M. WOOD, a citizen of the United States, residing at Schenectady, county of Schenectady, State of New York, have invented certain new and useful Improvements in Indicators for Liquid-Containing Vessels, of which the following is a specification.

It is important in the operation of power systems of various kinds, and more especially those intended for automobile service, to provide a means for indicating the level of the liquid in the tanks or vessels, whether the latter hold fuel or water. It is customary to put a gage-glass on the side of the tank or vessel and pipe it thereto above and below the working level. This is a fairly successful means for water-tanks, but is totally unsuited for fuel-tanks containing gasoline or similar fluid. When the glass of an automobile water-tank breaks, nothing serious happens if the operator notices it in time to close the cocks in the connections. If he does not, there is danger of being stalled. On the other hand, if a gage-glass is used on a gasoline-tank and it breaks there is great danger of setting the vehicle on fire and burning the occupants. This is particularly true if the tank is working under pressure. To avoid accidents, fuel-tanks are made without indicators, and a common way of determining the amount of fuel left is to insert a stick and observe how far from the end it is wet. Obviously such a practice is not a convenient or desirable one, and in any event it or any other method of inspecting which involves opening the tank can only be practiced by first relieving the tank of its pressure and then resubjecting it to pressure — a thing which is most inconvenient and necessitates a delay.

The present invention has for its object to provide a device for indicating the fluid-level of a closed vessel which is capable of withstanding any pressure to which the tank may be subjected, is practically indestructible, and is simple in construction.

In the accompanying drawings, Figure 1 is a side elevation of a tank fitted with my improved indicator. Fig. 2 is a vertical sec-

tion of the indicator, and Fig. 3 is a section taken on the line 3 3 of Fig. 2.

1 represents the ordinary tank of an automobile, and it may contain fuel or water, as desired. A pump 2 is arranged to put the 55 contents of the tank under pressure more or less great. The average fuel-tank works from fifty to one hundred pounds pressure per square inch, and this I have found to work satisfactorily with my improved indicator. 60 Situated at one end of the tank and piped to it above and below the normal fluid-level is a non-transparent tube 3, made of non-magnetic metal or other suitable material having closed ends. The construction is best 65 shown in Fig. 2, wherein 4 and 5 represent holders or elbows that are arranged to receive the pipes 6 and 7 from the tank and the main tube 3. The holders are provided with detachable screw-threaded caps 8, which are 70 suitably packed to make tight joints. It is to be noted that the tube 3 is made long enough to cover the opening from the pipes 6 and 7; but small passages 9 and 10 are provided to permit the contents of the tank to 75 enter the main tube. The object of thus extending the tube is to prevent the float 11 from being retarded, caught, or held in an inoperative position. The float 11 can with 80 advantage be made of cork; but other materials capable of floating can be employed, if desired. Mounted in the float, and preferably in the center, so as to balance it, is a small bar 12, of magnetic material. I have found hard steel to work satisfactorily; but 85 other metals may be employed, if desired. The float freely rides up and down within the tube as the level of the liquid in the tank changes.

In order that the operator may determine 90 the height of the liquid in the tank, a needle 13 is employed, which is carried by a movable sliding piece or sleeve 14, that surrounds the main tube 3. The needle can with advantage be polarized, as it will be more sensitive 95 with respect to the bar 12. I have shown a complete compass, but obviously any polarized needle will do as well. The compass box or support is provided with a screw-threaded end 15, that passes through a pro- 100

jection on the sleeve and engages with the main tube. It is desirable, although not necessary, to so arrange the compass box or support that when its face is turned upward the 5 sleeve is free to slide up and down on the tube and when it is rotated so as to face downward to clamp the sleeve in place. Obviously when the needle is adjacent to the bar 12 on the float it will be attracted, and its 10 movement can readily be observed. The shape of the pointer end also indicates whether or not it is attracted.

In operating my invention the tank can be filled in the usual way and sealed, after which 15 it can be put under any desired pressure by the pump 2. The main tube being made of metal or fiber and of suitable thickness, it will withstand any desired pressure. When the operator desires to ascertain the amount 20 of liquid in the tank, he releases the sleeve 14 by giving the compass a half-turn. This brings the needle 13 into view, after which the sleeve is adjusted up or down until a point is reached where the needle is strongly 25 attracted. This being found, the operator can tell exactly how much liquid there is in the tank. The sleeve can then be moved away or left in the last-mentioned position, as desired. The main tube 3 may or may not 30 be provided with indications 16, that preferably indicate quarts or gallons, depending upon the size of the tank. The liquid is drawn from the tank by the connection 17.

In order to make the detection of the fluid-level more easy, I provide a small magnet 18, which normally tends to attract the pointed or north end of the needle. The effect of this magnet on the needle is less, of course, than that of the magnetized bar 12. With the arrangement described a half-revolution of the 35 needle is always assured whenever it comes within a definite distance of the bar 12.

In accordance with the provisions of the patent statutes I have described the principle of operation of my invention, together 40 with the apparatus which I now consider to represent the best embodiment thereof; but I desire to have it understood that the apparatus shown is only illustrative and that the 45 invention can be carried out by other means.

What I claim as new, and desire to secure by Letters Patent of the United States, is—

1. In an indicating device, the combination 50 of a non-transparent tube, a float mounted within the tube, a body of magnetic material carried by the float, a sleeve which engages the tube and moves thereon, an indicator, a box therefor, and a screw-threaded means attached to the box and arranged to pass 55 through the sleeve and impinge on the tube for securing the indicator and the sleeve in position on the tube.

2. In an indicating device, the combination 60 of a non-transparent tube, a float mounted within the tube, a body of magnetic material

carried by the float, a sleeve which engages the tube, a compass-box capable of vertical and rotary movement, and a screw-threaded extension on the box which passes through the sleeve and clamps it to the tube when rotated in one direction and releases it when rotated in the opposite direction. 70

3. In an indicating device, the combination of a non-magnetic metal tube, a float mounted within the tube, a body of magnetic material 75 carried by the float, a compass-needle for indicating the position of the float, a box for the needle, a sleeve surrounding the tube, and a screw-threaded projection formed on the box for securing it in inverted position 80 when not in service.

4. In an indicator, the combination of a main tube, holders located at each end thereof, connections which lead from the holders at points between the ends of the tube and 85 carry liquid to and from the tube the said tube partially covering the openings in the connections, a float which is capable of moving up and down with changes in level of the liquid and is prevented by the tube from being affected by the connections, and a manually-adjusted polarized needle for indicating the position of the float. 90

5. In combination, a tank, a pair of holders each of which is provided with openings, a 95 tube which enters one of the openings in each holder and partially covers a second opening, connections which are attached to the tank and enter other openings in the holders, a float, a piece of magnetic material carried by 100 the float, a sliding sleeve surrounding the tube and engaging therewith, and an indicator having a screw-threaded portion which enters the sleeve and clamps it to the tube.

6. In an indicating device, the combination 105 of a non-transparent tube, a float mounted within the tube, a body of magnetic material carried by the float, a sleeve which engages the tube and slides up and down thereon, a compass-needle, a box therefor, and a screw-threaded projection on the box which passes through the sleeve and impinges on the tube when it is desired to clamp the box in a fixed position. 110

7. In an indicating device, the combination 115 of a non-transparent tube, a float within the tube, a body of magnetic material carried by the float, a sliding support surrounding the tube, an indicating device carried by the support which is affected by the body of magnetic material, and a screw-threaded clamping means formed on the indicating device itself for securing it in any desired position on the tube. 120

In witness whereof I have hereunto set my 125 hand this 10th day of December, 1902.

MONTRAVILLE M. WOOD.
